by W. E. Beatty, Atty.

UNITED STATES PATENT OFFICE.

ROY D. CONWAY, OF CHATHAM, NEW JERSEY, ASSIGNOR TO WESTERN ELECTRIC COMPANY, INCORPORATED, OF NEW YORK, N. Y., A CORPORATION OF NEW YORK.

TRANSMISSION SYSTEM.

Application filed March 29, 1920. Serial No. 369,802.

To all whom it may concern:

Be it known that I, Roy D. Conway, a citizen of the United States, residing at Chatham, in the county of Morris, State 5 of New Jersey, have invented certain new and useful Improvements in Transmission Systems, of which the following is a full, clear, concise, and exact description.

This invention relates to a telephone 10 transmission system. It relates more particularly to a telephone system in which a repeater is used in connection with a link or cord circuit for connecting line or trunk circuits to each other.

15 It has heretofore been customary in using repeaters in a link circuit to associate with such repeaters a number of balancing sets for balancing the line or trunk circuits to which the link circuit may be connected, in order to provide for rendering the repeater 20 paths connected to a line conjugate to each other. In such arrangements, it is necessary to have as many balancing circuits as there are line or trunk circuits of different 25 characteristics, which may be associated with the link circuit. Manual means are sometimes used for associating the proper balancing or artificial line with the repeater and with the connected line or trunk circuit.

30 An object of this invention is to provide improved means for rendering the repeater paths connected to a line conjugate to each other.

A further object is to provide automatic 35 means whereby the connected line or trunk circuit may be balanced when the connections are set up. This is accomplished by selecting means which automatically adjust in some cases the effective values of an 40 electrical network which is adapted to be associated with any desired line and which in other cases automatically adjust the effective turns of transformer windings in circuit with the network and the line in accordance with the characteristics of the 45 line to be balanced. A balancing network may be permanently associated with the output transformer so that the line of maximum impedance may be balanced merely 50 by adjustment of the effective number of

turns of transformer windings in circuit with the network and the line, and automatic selecting means may also be associated with the repeater which will operate to vary the characteristics of the artificial or 55 balancing network in accordance with the characteristics of other line or trunk circuits with which connection may be set up.

The invention will be understood by reference to the accompanying drawing which 60 shows a cord circuit having two one-way amplifiers of the vacuum bulb type connected therein, and having associated therewith automatic selector means for balancing the line circuits. The two way transmission of signals is made possible by the well-known wheatstone bridge balancing method. The jacks J and J' of two line 65 circuits which are provided with the usual signalling means, etc. (not shown) are indicated on the drawing. When the operator, upon receiving the proper signal inserts plug P at the answering end of her cord, into the jack J of a calling subscriber, the relay 1 is energized by a circuit 70 from ground, through battery, resistance R, relay 1, sleeve contacts of plug P and jack J, relay 2, to ground. Upon receiving the number of the desired party she then inserts the plug P' at the calling end of her 75 cord circuit into the jack J' of the called subscriber, thereby establishing a circuit from ground through battery, resistance R', relay 1', sleeve contacts of plug P' and jack J', relay 2', to ground. The contacts of relay 1 and 1' are thereby closed, but relays 2 and 2' being marginal, are not 80 operated.

The operator then presses her key K in order to associate the proper balancing 85 lines with the repeater for balancing the connected lines. Closing of key K establishes a circuit from ground through battery, wire 3, contact 4 of relay 1, wire 5, key K, wire 6, contact of relay 1', wire 7 relay 90 C, to ground. This operates relay C, thereby closing its upper and lower contacts. A relay such as relay C is provided for each 95 cord circuit, and the lower contacts of these relays are connected in series as indicated 100

in the drawing. Two other relays C_1 and C_2 corresponding to other cord circuits are shown, and it is obvious from an inspection of the connections of the same that when any one of the relays C , C_1 , C_2 , etc., is energized to cause the automatic selecting means to operate to select the balancing networks for two connecting lines, none of the other cord circuit selecting means can operate at the same time.

The closing of the upper and lower contacts of relay C , by means of the circuit above traced, establishes a circuit from battery through a lower contact of relay C , wires 8 and 9, upper contact of relay C , relay 1, sleeve contacts of plug P and jack J , relay 2 to ground. This energizes relay 2 thereby closing its contacts for a purpose to be described below.

20 The closing of the lower contact of relay C also establishes a circuit from battery through lower contact of relay C , wires 8 and 14, left contact of relay 25, wire 15, and relay 16 to ground, thus energizing relay 16 and closing its contacts. The current through wire 14 also divides at the point 14' and passes through relay 17, wire 18, resistance R_4 , through back contacts of relay 20, 20₁ or, 20₂, to ground, thus energizing relay 17 and closing its contact.

25 The closing of the contacts of relay 16 establishes a circuit from battery through the upper movable contacts of relay 16 and then through the three parallel circuits as follows: Marginal relay 21, resistance R_{a1} , motor magnet 22, extreme lower contact of relay 16 to ground marginal relay 21₁, resistance R_{a2} , motor magnet 22₁, intermediate lower contact of relay 16 to ground; and 30 marginal relay 21₂, resistance R_{a3} , motor magnet 22₂, lower contact of relay 16 to ground. This starts the motor magnets to operating, thereby revolving the wiper arms of the rotary selector switches S , S_1 , and S_2 . 35 One of the contacts of row 45 of each one of the rotary switches S , S_1 and S_2 is connected by means of the wires 10, 11 and 12, to the contacts of relay 2 so that these wires will all be grounded when relay 2 is energized. The 40 motor magnets 22, 22₁ and 22₂, step up the wipers, until they reach the points grounded through the contacts of relay 2, when the motor magnets are short-circuited and the wipers consequently rest on these grounded 45 points. The increased current through the marginal relay 21 due to the wire 23 being grounded through switch S and wire 10 will cause the marginal relay 21 to be energized, thereby closing its contact. A similar operation occurs with respect to the marginal relays 21₁, and 21₂, thereby closing their contacts.

50 Closing the contact of relay 21 establishes a circuit which may be traced from battery through the lower contact of relay C , wire 8,

front contact of relay 17, resistance R_1 , wire 19, relay 20, and front contact of relay 21 to ground thereby energizing relay 20 and locking the circuit to ground through its right-hand contact. The energization of the relay 20 opens the circuit from the wire 18 through the left-hand contact of relay 20. In a similar way, the short-circuiting of the motor relays 22₁ and 22₂, cause the operation of the marginal relays 21₁ and 21₂, thereby locking the relays 20₁ and 20₂ to ground and opening the remaining circuits from wire 18 through the outer contacts of relay 20₁ and 20₂ to ground. Removing of the grounds from wire 18, as just described, deenergizes relay 17, thus causing its back contact to close, thereby establishing a circuit from battery through the upper contact of relay C , wire 8, back contact of relay 17, slow-operating relay 24, resistance R_1 , wire 19, relays 20, 20₁, 20₂, in parallel, and through their inner front contacts to ground, thus keeping the relays 20, 20₁, and 20₂, locked and causing the operation of the relay 24.

55 The energization of relay 24 by means of its movable contact, establishes a circuit from battery through lower contact of relay C , wire 8, front contact of relay 24, slow-acting relay 25, to ground, thus closing all of the contacts of relay 25. Energization of relay 24 also opens at its back contact the circuit previously traced from battery through wire 9, lower contact of relay C , relay 1 and relay 2 thereby deenergizing relay 2 and causing its contacts to open and remove ground from wires 10, 11 and 12. Closing of the right-hand contact of relay 25 shifts battery on relay C through a circuit which may be traced from ground through battery, right-hand contact of relay 25, contact 4 of relay 1, contact of relay 1₁, key K , wires 6 and 7, relay C to ground. The energization of relay 25 also breaks the circuit through wire 15 at the back outer left-hand contact of relay 25 thereby deenergizing relay 16 whose contacts open and remove battery from the marginal relays 21, 21₁ and 21₂, and motor magnets 22, 22₁, and 22₂, thereby permitting the wiper arms of the switches S , S_1 and S_2 to remain in the positions to which they have been moved.

60 The tip and ring contacts of the plug P are connected to the transformer T and the line winding of the transformer T is connected by means of the wires 30, 30₁, through wires 32 and 32₁, to the wiper arms of the switch S_1 , which wipe over the associated two rows of contacts, thereby making connections with the proper capacity C_1 . The wires 30 and 30₁, are also connected through the wires 31 and 31₁, to the wipers of switch S_2 which wipe over the associated rows of contacts to connect the proper resistance R_1 .

65 A suitable number of points on the line

winding of the transformer T are connected to the rows 46, 47 of contacts of the switch S, so that the wipers of this switch S may connect the same to the pair of wires 29, 29₁, which lead to the primary winding of the transformer t.

The other winding of the transformer T is connected through wires 34, 34₁, to the output side of the vacuum bulb B, and the 10 secondary winding of the transformer t leads to the input side of the vacuum bulb A.

All of the corresponding contacts in the row 45 of the switches S of all the cord circuits will be connected in parallel to the 15 same wire 10 so that the wipers will be stopped at the proper point irrespective of the cord circuit with which the connection is set up. There will be as many contacts in the row 45 of contacts of switch S as 20 there are line circuits of different characteristics which it is desired to balance. The balancing network consisting of the elements R₁₂ and C₁₂ which correspond to the first position of switches S₁ and S₂ will be 25 such that the line circuit of minimum impedance may be balanced without shifting the wiper arms from their initial positions. When line circuits of other characteristics are connected, the selector switch S₁ and S₂ 30 may connect other balancer elements to the wires 30, 30' so as to obtain proper balancing. Or the proper balancing may be obtained for line circuits of other characteristics by allowing selector switches S₁ and S₂, 35 to maintain the same amount of capacity and resistance in the artificial line, the connection in the effective impedance of the artificial line being made by stepping selector S around until the proportions included 40 in the real line circuit and the artificial line circuit bear such a relation to each other that the desired balance is obtained. For example if S₁ and S₂ give the artificial line too high an impedance to balance the new 45 line selector switch S should operate to include more turns of the transformer windings in the real line circuit and less turns in the artificial line branch.

It is obvious that the connection of the 50 balancing elements to wires 30 and 30₁ may be made in other suitable ways besides the parallel relation described above. The connections of the outer contacts of the rotary switches S, S₁ and S₂ are so made that the 55 energization of the marginal relay 2 of any line circuit will cause the wipers of the rotary switches S, S₁ and S₂ to stop at such points that the proper adjustment is made 60 between the leads of the input of the transformer and the taps of the output transformer, and the appropriate balancing networks are also associated with the transformer T, in accordance with the characteristics of the particular line to which connection is made.

In order to trace the circuits by means of which the adjustment and selection of balancing networks for the called line are made, it will be noticed that the closing of the left-hand contacts of relay 25, above described, establishes a circuit from battery, lower contact of relay C, wire 8, left-hand contact of relay 25, wire 27, back contact of relay 24', relay 1', sleeve contacts of plug P', and jack J', marginal relay 2' to ground. 70 The increased current through relay 2', thereby causes it to operate and close its contacts so that the wires 10', 11' and 12' are grounded for a similar purpose for which the wires 10, 11 and 12 had been 80 grounded.

The energization of the relay 25 also establishes a circuit which may be traced from battery through lower contact of relay C, wires 8 and 14, left-hand contact of relay 25, wire 26, back contact of relay 25', and wire 15' from which it goes to a relay for the calling end of the cord circuit corresponding to the relay 16 of the answering end of the cord circuit. The current from wire 26 after passing through the back contact of relay 25' divides and part of it goes through relay 17' and wire 18' in exactly the same manner as has already been traced for the answering end of the cord circuit, thereby energizing relay 17'. Also the current from wire 26 passes through the front contact of relay 17', resistance R'₁ and wire 19' in exactly the same way as has been traced for the similar circuit at the answering end 100 of the cord circuit. The calling end of the cord circuit is provided with exactly the same equipment as is shown for the answering end and the operation is exactly the same. When the rotary switches have 105 reached the contacts which are grounded through the wires 10', 11', and 12', relay 17' becomes deenergized in the same way as already explained for relay 17. This closes contact from wire 26 through back contact of relay 17', relay 24', resistance R'₁, wire 19' to ground, in a manner similar to that already traced for the answering end of the cord circuit. The energization of slow 110 operating relay 24' closes a circuit which may be traced from battery to the lower contact of relay C, wires 8 and 14, left-hand contact of relay 25, wire 27 front contact of relay 24', through relay 25' to ground. The energization of relay 24' also opens 115 at its back contact the circuit previously traced through wire 27, relay 1' and relay 2', thereby deenergizing relay 2' and causing its contacts to open and remove ground from the wires 10', 11' and 12'. The energization of the relay 25' opens the circuit through the wire 15', thereby deenergizing the relay of the calling end of the cord circuit corresponding to the relay 16 of the answering end of the cord circuit, thus per- 120 125 130

mitting the corresponding rotary switches to maintain proper balancing of the called line.

The energization of the relay 25' also shifts battery on relay 25 through a circuit which may be traced from ground, through battery, right-hand contact of relay 25, wire 4, contacts of relay 1, key K, wire 6, contact of relay 1' left contact of relay 25', 10 left-hand contact of relay 24, through relay 25 to ground. Closing the left-hand contact of relay 25' opens the circuit through wire 7 and relay C to ground, thus causing the deenergization of relay C, so that the 15 selector apparatus associated with another cord-circuit may operate.

The tip and ring contacts of plug P' are connected to the transformer T' and connections are made to the repeater from the 20 transformer T' and to the selector switches for the calling end of the cord circuit in exactly the same way as has been explained for the answering end of the cord circuit.

By tracing the circuits, it is seen that 25 when an operator inserts the plugs P and P' into the jacks J and J', and presses her key, the rotary switches S, S₁ and S₂ operate first, to associate proper networks with the calling line, after which corresponding switches 30 operate to associate proper networks with the called line, and when the connections have been set up and the lines balanced, the relay C becomes deenergized, thereby permitting other cord circuits to be used for 35 setting up connections between two line circuits, and balancing the same. After the wipers of the selector switches have reached their proper contacts, the relays 17 and 17' are also deenergized as above explained. 40 When both plugs P and P' are withdrawn from the jacks, the relays 1 and 1' become deenergized and the apparatus is restored to normal. The wipers of the rotary switches remain in the positions to which 45 they have been moved, so that when other connections are set up, they will begin to be stepped up in order to reach the proper points for balancing the newly connected lines if such lines differ in characteristics 50 from the ones last connected. If the plug at one end only of the cord circuit is withdrawn from a line jack, its corresponding relay 1 or 1' is deenergized and when this plug is inserted into a line jack of a line 55 having a different characteristic, the relay 1 or 1' is again energized and the selector switches begin their travel to associate a proper balancing network with the newly connected line.

60 What is claimed is:

1. In a signaling system, a plurality of lines terminating at a central station, a link circuit, a repeater unit in said link circuit having input terminals and output terminals, a transformer in said link circuit,

connections from one set of said terminals to a winding of said transformer and means for automatically connecting said connections to different parts of a winding of said transformer in accordance with the characteristics of the line to which said link circuit is connected. 70

2. In a telephone system, a plurality of line circuits terminating at a central station, a link circuit, a repeater unit consisting of 75 two one-way amplifiers in said link circuit, an input transformer and an output transformer connected on each side of said repeater unit, and means for automatically connecting the leads from the primary windings of said input transformers to different parts of the line windings of said output transformers in accordance with the characteristics of the line circuits to which 80 said link circuit is connected. 85

3. In a telephone system, a plurality of line circuits terminating at a central station, a link circuit, a repeater unit in said link circuit, an input transformer and an output transformer connected to said repeater unit, 90 and a selector switch for automatically connecting the leads from the primary winding of said input transformer to different parts of the line winding of said output transformer in accordance with the characteristics of the line circuit to which 95 said link circuit is connected. 95

4. In a telephone system, a plurality of line circuits terminating at a central station, a link circuit, a repeater unit consisting of 100 two one-way amplifiers in said link circuit, an input transformer and an output transformer connected on each side of said repeater unit, and selector switches for automatically connecting the leads from the primary windings of said input transformers to different parts of the line windings of said output transformers in accordance with the characteristics of the line circuits to 105 which said link circuit is connected, and an operator's key for controlling said selector switches. 110

5. In a telephone system, a plurality of line circuits terminating at a central station, a link circuit, a repeater unit in said link circuit, an input transformer and an output transformer connected to said repeater unit, 115 and means for automatically connecting the leads from the primary winding of said input transformer to different parts of the line winding of said output transformer, and for associating a balancing network 120 with a line circuit, in accordance with the characteristics of the line circuit to which said link circuit is connected. 125

6. In a telephone system, a plurality of line circuits terminating at a central station, a link circuit, a repeater unit in said link circuit, an input transformer and an output transformer connected to said 130

- peater unit, and means for automatically adjusting the connections from the primary winding of said input transformer to different parts of the line winding of said 5 output transformer in accordance with the characteristics of the line circuit to which said link circuit is connected, and means for automatically associating a selected network with said connected line circuit.
- 10 7. In a telephone system, a plurality of line circuits terminating at a central station, a link circuit, a repeater unit consisting of two one-way amplifiers in said link circuit, an input transformer and an output 15 transformer connected to said repeater unit, a selector switch for automatically connecting the leads from the primary winding of said input transformer to different parts of the line winding of said output transformer 20 in accordance with the characteristics of the line circuit to which said link circuit is connected, and selector switches for associating resistance and capacity with said connected line circuit.
- 25 8. In a telephone system, a plurality of line circuits terminating at a central station, a link circuit, an operator's key associated with said link circuit, a repeater unit consisting of two one-way amplifiers 30 in said link circuit, an input transformer and an output transformer connected on each side of said repeater unit, and means operable when said key is pressed, for automatically connecting the leads from the primary 35 windings of said input transformers to different parts of the line windings of said output transformers in accordance with the characteristics of the line circuits to which said link circuit is connected.
- 40 9. In an electric system, a plurality of line circuits, a link circuit adapted to be connected between two of said line circuits, said link circuit comprising an impedance device and an artificial line, said impedance device 45 being in circuit with said artificial line and one of said connected lines, an electrical connection to an intermediate point of said impedance and electro-responsive means for varying the point on said impedance to 50 which said electrical connection is made in accordance with the characteristics of the line circuit to which said link circuit is connected.
- 55 10. In an electric system, a plurality of line circuits, a repeater circuit adapted to be connected between two of said line circuits, said repeater circuit comprising a transformer and an artificial line, said transformer having a winding in circuit with said 60 artificial line and one of said connected lines, an electrical connection to an intermediate point of said winding, and means acting in response to the connection of one of said line circuits to said repeater circuit for connecting said electrical connection to different 65 parts of said winding in accordance with the characteristics of the line circuit to which said repeater circuit is connected.
11. In an electric system, a plurality of line circuits, a repeater circuit adapted to 70 be connected between two of said line circuits, said repeater circuit comprising a transformer and an artificial line, said transformer having a winding in circuit with said artificial line and one of said connected lines, said artificial line having an impedance differing from the value of the impedance of one of said connected lines, an electrical connection to an intermediate point of said winding, and means acting 75 in response to the connection of said link circuit to one of said line circuits for connecting said electrical connection to different parts of said winding in accordance with the characteristics of one of the line circuits to which said repeater circuit is connected.
12. In an electric system, a plurality of line circuits, a repeater circuit adapted to 80 be connected between two of said line circuits, said repeater circuit comprising a transformer and an artificial line, said transformer having a winding in circuit with said artificial line and one of said connected lines, said artificial line having an impedance differing from the impedance of one of said connected lines, said winding having a plurality of taps an electric circuit adapted to be connected to one of said 85 taps, and electro-responsive means for changing the tap to which said last mentioned electric circuit is connected in accordance with the characteristic of one of the line circuits to which said repeater circuit is connected.
13. In an electric system, a plurality of line circuits, a link circuit adapted to be connected between two of said line circuits, a Wheatstone bridge type of network in said system, one arm of which comprises one of said line circuits, a second arm of which comprises said artificial line, a third arm of which comprises a circuit for incoming currents for said link circuit, a fourth arm of which comprises a circuit for outgoing currents for said link circuit, an impedance device, a portion of which is in said first arm, another portion of which is in said second arm, and electro-responsive 105 means for varying the relative proportions of said impedance included in said first two arms in accordance with the characteristics of the line circuit in said first arm.
14. In combination, a signaling line, an artificial line for balancing said signaling line, and means for determining a characteristic of said artificial line, said means comprising a plurality of stationary contacts, a movable member cooperating with said contacts and electroresponsive means depending 110
- 120
- 125
- 130

upon a characteristic of said signaling line for varying the position of said movable member.

15. In combination, a signaling line, an artificial line comprising impedance elements for balancing the said signaling line, and means for varying the effective value of said impedance element, said means comprising a plurality of stationary contacts each connected to a point on said impedance, a movable member cooperating with said contacts, and electroresponsive means depending upon a characteristic of said signaling line and operative only after said signaling line is connected to said artificial line for varying the position of said movable member.

16. In combination, two line sections, a two-way repeater circuit between said line sections, an artificial line for balancing each of said line sections, a rotary switch for varying the effective value of an element of one of said artificial lines, and an electroresponsive means for operating said rotary switch to a position determined by a characteristic of its associated line section.

17. In an electric system including a plurality of lines, a link circuit, said link circuit having a transformer winding in series therein and said link circuit being adapted to be connected between two of said lines at a time with one end of said winding connected to one of said two lines and the other end of said winding connected to the other of said two lines, said system also including an adjustable connection to said winding, and electroresponsive means for moving said connection to a position on said winding which is intermediate to points of connection of said winding to said two lines and which is determined by a characteristic of one of said two lines, and for moving said connection to a second position determined by a characteristic of another of said lines subsequently connected to said link circuit.

18. In an electric transmission network, a circuit, a multi-winding transformer, circuit means, means connected between said circuit and said circuit means and comprising a winding of said transformer, said circuit means presenting a variable impedance to said connected means, a circuit adjustably connected to said winding of said transformer, a circuit in conjugate relation to said adjustably connected circuit, and means operating in response to variation of said variable impedance for adjusting said ad-

justable connection to such a position on said winding that said conjugate relation is maintained.

19. In combination, a plurality of signaling lines, each having a different characteristic impedance, a multi-winding transformer, a line impedance balancing network, means including a winding of said transformer for connecting said network to each of said lines, one line at a time, with said winding of said transformer in series with said connected line and said network, repeater terminals connected to a second winding of said transformer, other repeater terminals, and means for connecting said other repeater terminals to a common terminal of said network and said connected line, and to any one of a plurality of intermediate points of said first winding, said points of connection to said first winding being so located on said first winding that said first winding may be unequally distributed on the two sides of one of said points an amount sufficient to compensate for the difference in impedance between said connected line and said network.

20. In combination, a plurality of signaling lines, each having a different characteristic impedance, a multi-winding transformer, a line impedance balancing network, means including part of the windings of said transformer for connecting said network to each of said lines, one line at a time, repeater terminals connected to another part of the windings of said transformer, other repeater terminals, and means whereby said other terminals may be connected to such points on said first part of said transformer windings that when one of said lines is connected to said network by said first mentioned means, said other repeater terminals are prevented from receiving electromotive forces impressed on said line through said second part of said transformer windings, and whereby said other terminals may be connected to such points on said first part of said transformer windings that when another of said lines is connected to said network by said first mentioned means, said other repeater terminals are prevented from receiving electromotive forces impressed on said line through said second part of said transformer windings.

In witness whereof, I hereunto subscribe my name this 25th day of March A. D., 1920.

ROY D. CONWAY.
